UNITED STATES PATENT OFFICE

135,746

DESIGN FOR A PLACARD OR THE LIKE

Herbert M. Wertz, Toledo, Ohio, assignor to The Toledo Steel Products Company, Toledo, Ohio, a corporation of Ohio

Application December 31, 1942, Serial No. 109,168

Term of patent 7 years

To all whom it may concern:

Be it known that I, Herbert M. Wertz, a citizen of the United States and a resident of Toledo, Lucas County, Ohio, have invented a new, original, and ornamental Design for a Placard or the like, of which the following is a specification, reference being had to the accompanying drawings, forming a part thereof.

In the drawings:

The essential features of my design reside in the parts shown in full lines.

I claim:

The ornamental design for a placard or the like, as shown and described.

HERBERT M. WERTZ.
